UNITED STATES PATENT OFFICE.

HARRY C. CLAY, OF COLUMBUS, INDIANA, ASSIGNOR TO EMERSON-BRANTINGHAM COMPANY, OF ROCKFORD, ILLINOIS, A CORPORATION OF ILLINOIS.

VALVE-GEAR MECHANISM.

1,425,631.

Specification of Letters Patent. Patented Aug. 15, 1922.

Application filed January 27, 1919. Serial No. 272,224.

To all whom it may concern:

Be it known that I, HARRY C. CLAY, a citizen of the United States, residing at Columbus, in the county of Bartholomew and State 5 of Indiana, have invented certain new and useful Improvements in Valve-Gear Mechanism, of which the following is a specification.

This invention relates in general to valve 10 gears for use on steam engines and particularly to that type of valve gears commonly known as "reversing gears".

The reversing gear disclosed herein is of that type which insures that the amount of 15 lead shall be uniform for all points of cut-off in either direction of motion so that the points of cut-off within the working range will bear the same relation to the stroke of the piston at both ends irrespective of 20 whether the crank shaft is being driven by the piston over or under. Such a valve gear mechanism is disclosed in my prior Patent No. 673,859, granted May 14, 1901, and my present invention pertains more particularly 25 to the means by which the valve gear mechanism is actuated and controlled and by which the speed of the engine is also regulated and controlled through the throttle valve.

30 One of the primary objects of this invention is the provision of simple and efficient means by which the speed of the engine, its direction of travel and the point of cut-off may all be regulated and controlled to a fine 35 degree of nicety from a single controlling lever so that the operator may at all times have the engine under perfect control and may quickly and easily change the speed, direction of travel or point of cut-off with 40 one hand by the manipulation of the single controlling lever.

In addition to simplicity of construction, efficiency of operation and cheapness of manufacture, my invention embraces other 45 objects and advantages which will be readily appreciated by those skilled in the art as the invention is better understood by reference to the following drawings upon which one preferred embodiment of the invention is 50 illustrated.

Referring to the drawings—

Fig. 1 is a rear end elevation of an engine equipped with my invention;

Fig. 2 is a longitudinal sectional view

taken substantially through the center of the 55 engine shown in Fig. 1; and

Fig. 3 is a fragmentary plan view showing the limiting stops on the reversing arm.

By reference to the drawings it will be observed that I have illustrated my invention as applied to a double engine, the type illustrated being particularly adapted for 60 operating a hoisting winch, but it will be manifest that the invention is capable of application to any other type of steam engine with equally favorable results. On the drawings, which illustrate the type of engine selected for purposes of illustration, reference character 5 indicates the engine base, 6 the steam piston valve, and 7 the 70 cylinders. Steam is supplied from the usual boiler through a steam line 8 which is connected at 9 to the manifold 11, which, as will be evident from Fig. 2, comprises a live steam passage 12 with which the pipe 8 75 communicates and an exhausting passage 13 communicating with a flanged fitting 14 to which the exhaust line may be connected in the usual manner. The crank shaft 15 is driven from the cylinders through the usual 80 cranks and connecting rods (not shown) and the shaft 16 upon which the winding drum of the winch is mounted is driven from the crank shaft 15 by suitable reducing gearing. The structure thus far described may be of 85 any usual or preferred construction since my invention is not limited, as before stated, to any particular type of engine.

Upon the crank shaft 15 there is mounted the usual eccentric 17 embraced by the eccentric strap 18 having a radial arm 19. Pivoted to the outer end of the arm 19 at the point 21 is a controlling link 22 to the outer end of which is pivoted at 23 one arm 24 of a bell crank shaped reversing lever, the other 95 arm 25 of which extends upwardly as shown in Fig. 2. It will be manifest that by swinging the reversing arm 25 forwardly or rearwardly the eccentric arm 19 will be correspondingly moved rearwardly or forwardly 90 with respect to its eccentric. Pivoted to the eccentric arm 19 at 26 is a link 27 pivoted at its opposite end to the arm 28 of a bell crank lever pivoted on the engine frame at 29, the other arm 31 of the lever being pivotally 100 connected to the outer end of a valve link 32 the opposite end of which is pivoted within the steam chest to the cut-off and reversing 105

valve in the usual manner. It will be understood that by moving the reversing arm 25 forwardly or rearwardly the position of the valve will be changed to effect reversal of the engine and by proper adjustment of the reversing arm the point of cut-off may be regulated to a fine degree of nicety.

The mechanism for actuating and controlling the reversing arm 25 comprises a controlling lever 33 located in a position convenient and accessible to the operator, and suitable connections between this lever and the arm 25. From Fig. 1 it will be observed that a rock shaft 34 is mounted in suitable support or brackets 35 so as to extend transversely of the engine preferably above the cylinders. At one end a bifurcated yoke 36 is fixedly secured upon this shaft and the controlling lever is pivotally mounted in this yoke upon fulcrum screws 37 the inner ends of which are seated in suitable sockets formed on the lever 33. It will thus be seen that the lever is capable of movement in two planes, that is, it may be swung about the fulcrum screws 37 longitudinally of the shaft for a purpose which will be later described, and it may be swung in a plane at right angles to the shaft in which event the shaft will be rocked with the lever, since no movement of the lever transversely of the shaft is permitted by the lever mounting. The shaft 34 is equipped with an upwardly extending arm 38, two being shown in the present instance since this is a double engine, and the upper end of this arm is connected to the reversing arm 25 by a link 39. When, therefore, the controlling lever 33 is rocked forwardly or rearwardly this motion is transmitted through the link 39 to the arm 25 and the movement is thereupon modified and transmitted through the valve gear mechanism to the reversing and cut-off valve.

In order that the maximum cut-off may be established for each direction of the engine, I have mounted upon the reversing arm 25 a plurality of stops 41 and 42, which, when the valve is thrown into the extreme desired positions, abut respectively against the engine frame to thereby limit the extent of throw of the valve and insure the maintenance of the valve in its extreme adjusted positions.

The same controlling lever 33 is utilized to actuate the throttle valve which controls the steam supply to the cylinder. This throttle valve may be of the usual sliding type and is indicated by reference character 43 in Figs. 1 and 2. The valve stem 44 is connected at 45 with a lever 46 fulcrumed at 47 upon a suitable bracket 48. The upper end of the lever is connected by link 49 with the lower end of the controlling lever 33, a ball and socket joint 51 being employed to connect the link to the control-

ling lever so that there will be no binding when this lever is swung to rock the shaft 34. A contraction spring 52 attached at one end to the lever 46 and at its other to a clip 53 embracing the steam line 8 tends to normally close the throttle valve so that if the operator's hand should slip off the controlling lever the engine will be automatically stopped.

It should be manifest from the foregoing that I have provided a system of control for a reversible steam engine in which the point of cut-off and the speed of the engine as determined by the position of the throttle valve are all controlled from a single lever so that the operator with his hand on the lever may swing it in a plane longitudinally of the engine for reversing purposes and for regulation of the point of cut-off and may swing it transversely of the engine to open and close the throttle. Should any accident happen the throttle will automatically close, thus obviating any danger of disaster which might result from continued uncontrolled operation of the engine.

It is believed that my invention and many of its attendant advantages will be understood from the foregoing without further description and, while I have shown and described one preferred embodiment, it should be understood that various changes in the size, shape, proportion and arrangement of the various parts may be resorted to without departing from the spirit of the invention as defined in the following claims.

I claim:

1. The combination with a throttle valve and a valve gear mechanism including a reversing arm, of a rock shaft, a yoke fixed to the rock shaft, fulcrum screws carried by the arms of the yoke, a control lever pivotally supported upon and between said fulcrum screws to swing in a plane parallel with the axis of said rock shaft, an arm fixed to the rock shaft and connected to the reversing arm, and a connection between the controlling lever and the throttle valve, whereby to operate the throttle valve by swinging said lever longitudinally of the shaft and to operate said reversing arm by swinging the lever at right angles to the shaft.

2. The combination with a throttle valve and a valve gear mechanism including a reversing arm, of a rock shaft, a yoke fixed to one end of the rock shaft, a control lever disposed between and pivotally mounted upon said arms of said yoke, an arm fixed to the rock shaft and connected with said reversing arm, and a connection between the lower end of said lever and the throttle valve, whereby to operate said valve and reversing arm by movement of the lever in transverse planes.

3. The combination with a throttle valve

and a valve gear mechanism including a reversing arm, of a rock shaft, a yoke fixed to one end of the rock shaft and reaching at its outer end substantially beyond the adjacent end of the shaft, a control lever disposed between and pivotally mounted upon the extended ends of the yoke, a connection between the rock shaft and reversing arm, and a connection between the control lever and throttle, whereby to operate the reversing arm and throttle by movement of said lever in transverse planes. 10

HARRY C. CLAY.
